UNITED STATES PATENT OFFICE.

LUCIEN GESCHWIND, OF PARIS, FRANCE.

ROASTING FURNACE.

Application filed September 19, 1923. Serial No. 663,714.

To all whom it may concern:

Be it known that I, LUCIEN GESCHWIND, a citizen of the French Republic, and residing at 117 Bd. Haussmann, Paris, France, ⁵ have invented certain new and useful Improvements in Roasting Furnaces, of which the following is a specification.

My invention relates to roasting furnaces of the Spirlet type.

10 The Spirlet furnaces comprise a plurality of circular hearths of refractory material which are superposed and are alternately fixed and movable. Each hearth consists of a thick plate of refractory substance ¹⁵ which is slightly convex at the top, said plate being mounted in a circular metallic frame. The frames of the fixed hearths are secured to a stationary structure whilst the frames of the rotating hearths comprise an ²⁰ outer circular rail resting upon rollers whose axles are secured to the said stationary structure; the movable hearths are rotated by suitable means. The teeth of the raking portion consists of blocks of refractory material having the shape of triangular prisms with vertical edges whose rectangular base is embedded in the lower face of each fixed hearth, said blocks being disposed according to a spiral, or at least in such ²⁵ manner that the operation of each block shall not be hindered by the succeeding block and that the proper cleaning will be ensured.

30 The said furnaces are used at the present time solely for the roasting of zinc blende. By reason of the close spacing of the hearths and the reduced radiation, the combustion is very active and temperatures of 850 to 900 degrees C. are readily attained. ³⁵ Since it is important for the roasting process as well as for the preservation of the refractory material that such temperatures should not be exceeded, only a relatively small quantity of ore can be treated in a ⁴⁰ day's run. A furnace having 4.70 metres diameter with four hearths whereof two are movable, may provide for a daily charge of 4 to 5 tons of lead-bearing zinc blende containing 14 per cent of lead and 28 per cent ⁴⁵ sulphur. The oxidizing air should be supplied in the heated state, but this requires the use of coal in the proportion of some 6 per cent of the raw ore.

50 In a furnace of this class it is only feasible to roast from 2 to 2.5 tons of pyrites per day, by reason of the heat produced by

the combustion of the ore which for a given weight of ore is much greater than in the case of zinc blende, since the pyrites contain about 50 per cent of sulphur and its ⁶⁰ combustion is more exothermic.

Metallic teeth, even when cooled by a circulation of air, are unable to withstand the high temperatures prevailing in the furnace, so that it becomes necessary to use clay for ⁶⁵ their construction; but the clay is found to combine with the elements of the zinc blende, chiefly the lead, thereby forming crusts containing silicate and lead.

70 For this reason the said teeth must be cleaned several times a day with a metallic tool, thus requiring hand labour and causing breakage; such teeth cannot in fact last for more than from 3 to 6 months in the regions of the greatest heat, and this requires a frequent stoppage of the furnace ⁷⁵ and reconstruction of the hearths.

But with the clay in current use it is not feasible to make teeth which have a flat shape, as these would be very easily broken, ⁸⁰ and hence it was found necessary to give to such teeth the shape of a triangular prismatic mass whose large part is situated at the rear; in this case the hearth is covered during the raking operation by the whole surface of the said rear portion, leaving between each row of ore an empty annular ⁸⁵ space having in fact the width of this rear part.

90 Further, depending as before upon the fragile nature of the clay, it was not feasible to employ a great number of teeth and to give them when proceeding from the centre a suitable section corresponding to the reduced amount of the rows of ore relative to the diameter, so that when proceeding towards the exterior, the annular prisms of ore become continually of smaller size, and hence the surface of the hearth is utilized for the roasting in a very defective manner and the amount of ore circulating in the furnace is very small. But since there is a direct relation between the sojourn of the material in the furnace, namely, the duration of the roasting, and the ⁹⁵ weight of the material within the furnace, the ore will remain but a short time in the Spirlet furnace, and in fact this may be estimated at only six hours.

100 On the other hand, the raking plane of the tooth is vertical, so that during the travel of the mass of ore when roasting, the

prisms forming the mass will break against the tooth, their base will diminish, and hence there will be less friction upon the hearth. For this reason the prisms will move along solely by a sliding action, and the mass of ore will hardly be stirred.

My U. S. Patent No. 1,480,525 of January 8, 1924 relates to a form of metallic teeth which obviates the last-mentioned drawbacks to some extent by enabling the integral utilization of the hearth for the roasting and by providing for a thorough stirring of the ore. The first-mentioned drawbacks, namely, relating to the temperature, the formation of crusts and the like, are eliminated in our present invention by the use of special metallic rakes which are of hollow construction and are water-cooled. Each hearth consists of two like halves made of refractory material between which is fitted a diametrical rake of the said type, made of cast iron or steel, it being supported in the same manner as the hearth by the circular metallic frame of the latter; for the stationary hearths, the rake is hollow for the entire length, and the water enters at one end and is discharged at the other; for the movable hearths, the water inlet and outlet are both disposed at the central part of the rake, employing two concentric tubes situated upon the axis of the furnace.

With the said arrangement combined with the above-mentioned special teeth, I am enabled with the use of a Spirlet furnace of the size above stated to attain and even to exceed a daily output of 8 or 9 tons of zinc blende having 28 per cent sulphur, this being double the usual output, while at the same time dispensing with the auxiliary heating required with the Spirlet furnace. With the same furnace I was enabled to attain a daily output of 6 to 7 tons of pyrites.

The following description and appended drawings relate to a constructional form of the improved furnace according to the invention.

Fig. 1 represents in section and in elevation, with parts broken away, the general arrangement of a Spirlet furnace comprising the devices according to the invention.

Figs. 2 and 3 represent on a smaller scale diagrammatic plan views of a fixed and a rotating hearth.

Fig. 4 represents on a scale intermediate between that of Fig. 1 and of Figs. 2 and 3, a transverse section of one of the hearths.

The furnace shown in Fig. 1 comprises three fixed hearths 1, 2, 3 and two movable hearths 4, 5. Each fixed hearth is secured to a circular frame 6 provided at the exterior with a circular rail 7 mounted upon stationary supports, not shown. Each movable hearth as 4 is secured to a circular frame 8 provided at the exterior with a circular rail 9 adapted to rest upon vertical

rollers, not shown, whose axles are secured to a stationary structure. The said movable hearths are rotated by suitable means.

Each fixed hearth consists of two halves 10, 11 made of refractory material, Fig. 2, mounted in the frame 12 and separated at the middle by a metallic rake 13 which consists of a diametrical tube connected at one end with the cooling water inlet conduit 14 and at the other end with the outlet conduit 15. The hollow rake 13 is preferably provided at the interior with a vertical partition 16 making it more rigid and ensuring an increased water cooling surface, so that for a given circulation and within a given time the heat removed will be greater than without the use of the said partition. Each arm of the rake 13 is provided on its lower surface with metallic teeth 17, 18, 19, etc., which are preferably cast in one with the rake and have the form, dimensions, disposition and inclination as set forth in said U. S. Patent No. 1,480,525.

Each of the movable hearths as 4 consists of two halves 20, 21, Fig. 3 made of refractory material and mounted in the frame 22; between the said parts is disposed the rake 23 which is also mounted on said frame. The rake 23 is provided in each of its arms with a longitudinal partition 24, 25 extending from the middle to within a short distance from the end of the rake. At the central part of the rake are formed, by walls of suitable shape, the two chambers 26, 27 one of which, 26, is connected for example with a central vertical tube 28 and with two chambers 24', 25' situated on the same side of the partitions 24, 25; the second chamber 27 is connected with a tube 29 coaxial with and surrounding the tube 28, as well as with the two chambers 24'', 25'' situated on the other side of the partitions 24, 25. The inner tube 28 is connected at the top with a supply tank 30, Fig. 1; the outer tube 29 is closed at the top and is provided with a cock 31 disposed above a water return tank 32. In this manner the cooling water from said supply tank proceeds through the inner tube 28, the supply chamber 26, the two chambers 24', 25' of the rake arms, the two chambers 24'', 25'' of said arms, the chamber 27, the outer tube 29, and thence returns through the cock 31 to the tank 32. Each rake of a movable hearth, as 4, has at the lower part the teeth 33, 34, 35, etc., which are preferably cast in one with the rake, and in the same manner as for the fixed hearths are given the forms, dimensions, disposition and inclination as mentioned in my above mentioned prior patent.

The outer tube 29 supplying the rake of the movable hearth 4 is provided with a downwardly extending flange 36 engaged in a trough 37 containing sand and disposed

upon the rake of the upper fixed hearth 1, so as to form a tight joint in the manner already used in other pipes or furnaces. The lower movable hearth 5 is provided with 5 solid teeth of refractory material as used in the known Spirlet furnaces, since these teeth, which act upon the last hearth which has now become considerably cooled by the air entering the furnace, are much less subject to damage.

10 The said furnace arrangement is operated in the following manner:

The ore in a suitably pulverized condition is introduced through an aperture in the 15 upper fixed hearth 1 which is situated near the periphery and at the same distance from the centre as the farthest tooth of the set. The ore drops upon the upper movable hearth 4 which in the case represented by 20 the figure, when turning in the counter-clockwise direction, will bring the circular outer portion of the material adjacent the part of the tooth 17 which is farthest from the centre; said tooth will move this circular portion towards the centre, by a distance equal to the difference between the distances from the centre to its inner and its outer edge, while at the same time completely overturning the portion of material which 25 is adjacent the tooth. The said portion of material which is thus moved towards the centre will then be brought adjacent the farthest tooth from the centre 17" upon the opposite arm of the rake. The material 30 is thus moved inwardly will then be brought adjacent the tooth 18 which overturns it and moves it still further towards the centre, and so on. The pulverized ore thus reaches the central region of the hearth 4; this 35 portion is provided with apertures, not shown, through which it drops upon the fixed hearth 2, in the region covered by the tooth 33. The teeth 33, 34, 35, 33', 34', 35' are mounted in the contrary direction to the 40 teeth of the rake of the upper fixed hearth 1, whereby the ore is caused to travel from the centre to the periphery of the fixed hearth 2, on the same principle as in the preceding case. The latter hearth is in turn 45 provided with an aperture near the periph-

ery in the region corresponding to the outer tooth. The ore is again brought towards the centre of the movable hearth 5 and is then dropped upon the lower fixed hearth 3 and is brought to the periphery 55 by the rake teeth, not shown, of the movable hearth 5. At this point it is discharged in the known manner through the apertures 40 of a fixed frame 41 and falls into the receptacles 42 in which the material is contained. 60 The air inlets 43 situated at the lower part of the brickwork provide for the admission of air through the lower part of the furnace, the air circulating in the furnace in the contrary direction to that of the travel 65 of the ore.

As observed in the preceding description which sets forth the operation of the furnace, the arrangement according to the invention utilizes the entire surface of the 70 hearths.

What I claim is:

1. In a furnace for roasting ores having 75 hearths of a refractory nature and circular form, which are superposed and are alternately fixed and rotating, an arrangement of furnace rakes cooled by water circulation comprising refractory hearths each consisting of two semicircular portions, a circular metallic frame supporting each hearth, a hollow diametrical metallic arm interposed 80 between said portions of each hearth, means whereby a cooling fluid is enabled to circulate within said hollow arm and metallic rake teeth provided on said arm, which is 85 supported by the circular frame of the hearth.

2. In a furnace for roasting ores having 90 hearths of a refractory nature and circular form, which are superposed and are alternately fixed and rotating, an arrangement of furnace rakes cooled by water circulation, as claimed in claim 1, in which the rakes for stationary hearths are hollow throughout 95 the whole length, the water of circulation entering at one end and issuing from the other.

In witness whereof I have hereunto set my hand.

LUCIEN GESCHWIND.
